UNITED STATES PATENT OFFICE.

EDWARD B. GIBFORD AND CHARLES WALKER GIBFORD, OF ADRIAN, MICHIGAN.

CARBURETOR VALVE.

Application filed December 20, 1920. Serial No. 431,889.

To all whom it may concern:

Be it known that we, EDWARD B. GIBFORD and CHARLES W. GIBFORD, citizens of the United States of America, residing at 5 Adrian, in the county of Lenawee and State of Michigan, have invented certain new and useful Improvements in Carburetor Valves, of which the following is a specification, reference being had therein to the accompanying 10 drawings.

This invention relates to carburetors and has among its objects to provide means for more effectively commingling the liquid fuel with the air, to so construct and arrange 15 the mixing chamber that the air upon entering the mixing chamber will be deflected so as to thoroughly commingling with the liquid fuel; to so construct and arrange the parts that in the manufacture of the carburetor the necessity of coring is avoided, the mixing chamber being preferably divided so as to facilitate the manufacture 20 and assembly and to permit of ready access to the various working parts; and in general to provide a new and improved construction of the character above referred to. The invention further resides in various 25 features and in such combinations and arrangements of parts as will more fully hereinafter appear.

In the drawings:

Figure 1 is a perspective view of the carburetor with the cap of the float chamber and one section of the mixing chamber removed;

Figures 2 and 3 are perspective views of the cap and removable mixing chamber section respectively;

Figure 4 is a central cross-section through 40 Figure 3;

Describing in detail the particular embodiment of my invention shown in the drawings, 1 designates the carburetor which comprises a float chamber 2 and a mixing 45 chamber 3. These chambers are preferably cast integral with a connecting web portion 4. The latter has a horizontal passageway 5 leading from the inside of the float chamber to a vertical passageway 6. At its lower 50 end the passageway 6 is provided with a suitable drain or pet-cock 7, while at its upper end it communicates with the mixing chamber 3 through a port 8. This port is controlled by metering pin 9 which extends 55 through the upper side of the casing and

through the bushing 10 threadedly engaging and extending through the casing.

Suitable means are provided for feeding the liquid fuel from the float chamber 2 to the mixing chamber 3 through the port 8. In the particular construction shown, the feeding is controlled by maintaining a constant level in the float chamber. A float 22 mounted on the stem 23 of a suitable valve is employed for this purpose, the construction being such that whenever the liquid level in the float chamber is sufficient to maintain the proper level in the passageway 6, the float will be raised sufficiently to close the valve in the inlet pipe 24. The operating level can be varied by removing the cap 25 and adjusting the spring clip 26 which has a slotted portion surrounding the stem 23 and adapted to yieldably engage in one of a series of annular grooves 27 in the stem, the clip being secured to the float 22. The cap 25 is removably held upon the float chamber 2 by a spring 28 pivoted to the wall of the mixing chamber.

After passing through the port 8 the fuel is commingled with the air in the mixing chamber 3, the particular construction and operation of which chamber forms an important feature of my invention. In detail the chamber comprises a central cylindrical portion 29 and inclined walls 30 and 31 arranged upon opposite sides of the cylindrical portion. To facilitate the manufacture, the inclined wall 31 is preferably formed on the removable section or cap member 32 secured to the cylindrical section by screws or other securing means passing through co-operating lugs 33. The valve 34 controlling admission of air to the mixing chamber is carried by the removable cap member 32, while the port 8 through which the gasoline or other liquid fuel enters, extends transversely through the side wall of the cylindrical portion 29 and substantially at the center thereof. The valve 34 is in the form of a poppet valve normally held to its seat 35 by a spring 36. The arrangement is such that whenever there is suction placed upon the discharge passageway of the carburetor, leading to the intake manifold, the valve 34 will be drawn away from its seat and air admitted to mix with the liquid fuel drawn through the port 8. Owing to the position of the valve, and the novel arrangement of the inclined walls 30 and 31 the air

entering around the periphery of the valve will be deflected at various times by the inclined walls and the cylindrical wall so as to produce eddies. The employment of the enlarged mixing chamber having the walls arranged substantially as shown in the drawings assures the desired mixture in the chamber. A further feature of the invention resides in making the upper end of the port 8 cup-shaped to insure a supply of the liquid fuel, particularly in starting.

For adjustably controlling the amount of air fed around the periphery of the valve 34, means for varying the amount of opening of this valve away from its seat is provided. In detail, the stem 37 of the valve extends through the guide way 38 formed by a bushing threadedly engaging the hub of the spider 39 upon the cap member 32. The free end of the stem has a threaded engagement with the outer apertured end of a cap 40 within which is the spring 36 coiled around the stem and abutting the washer 41. 42 is a lock nut threaded upon the outer end of the stem for maintaining the cap in adjusted position. Rotation of the valve stem 37 is prevented when rotating the cap 40 and lock nut 41 by means of the pin 43 extending through the stem and slidably engaging at its opposite ends the longitudinal slots 44 in the guideway 38.

In addition to the adjusting means above described, for controlling the amount of opening of the air valve 34 there is a rockable member 45 which is pivoted at 46 upon the cap member 32 and slotted at 47 to receive the valve stem. This slotted portion is elongated and thickened towards one end so as to provide an inclined surface 48 riding between the flange 49 at the outer end of the guide way 38 and the abutment washer 41. Normally this rockable member is positioned so that its thinnest portion is between the flange 49 and the abutment washer 41 but whenever the operator wishes to temporarily restrict the amount of opening of the valve it is only necessary to rock the member 45 about its pivot thus decreasing the distance between the abutment washer 45 and the cap 40, the ports being so arranged that at the end of this rocking movement there is no play between the abutment washer and cap and consequently the valve 34 cannot leave its seat.

In order to secure better commingling of the air with the liquid fuel and to permit of a limited amount of air entering the mixing chamber of the carburetor under certain conditions, as when the engine is running idle, the valve 34 is formed of two parallel spaced discs 50 and 51, the outer one of which, 51, is adapted to engage the seat 35 while the inner one 50, has its periphery slightly spaced from the inclined wall 31 when the other is seated. The outer disk 51 has the

axial aperture 52 therethrough and the valve stem 37 is hollow, whereby air can be drawn through the valve stem and outer disk and pass into the mixing chamber around the periphery of the inner disk when the outer disk is held to its seat by the rockable member 45. With this arrangement the strength of the coil spring 36 is not excessive so that it will properly function when the valve is released from its seat.

To prevent any air entering the mixing chamber, for instance, when the engine is being started, I have provided the closure 53 secured to the rockable member 45 and adapted to close the outer open end of the valve stem 37 when the latter is swung to the limit of its travel in the closing direction to maintain the valve seated.

From the above description it will be apparent that the admission of air to the mixing chamber is controlled by adjusting either the rockable member 45 or by adjusting the cap 40 and lock nut 41.

The construction as an entity is one in which very accurate adjustment can be made and the parts are so arranged that all portions of the carburetor are readily accessible either for repair or adjustment. Moreover, the novel construction of the mixing chamber not only secures a better mixture of the fuel and air but also permits the more economical manufacture and assembly of the parts owing to the meeting edges of the removable section and the main section lying in substantially the plane of one edge of the cylindrical portion. It will be understood that suitable gaskets are employed where they are necessary and that various changes in details of construction and arrangements of parts can be made within the scope of the appended claims.

What we claim as our invention is:

1. In a carburetor, the combination with an air inlet passage, of a valve controlling said passage, a stem for said valve, a cap upon said stem, a coil spring within said cap and engaging its outer end, and a wedge-shaped member movable transversely of said stem and supporting the inner end of said spring.

2. In a carburetor, the combination with an air inlet passage, of a valve controlling said passage, a stem for said valve, a guideway for said stem permitting of longitudinal movement thereof, a cap threadedly engaging the outer end of said stem, a washer sleeved upon said stem at the inner end of said cap, a coil spring surrounding said stem and abutting said washer and the outer end of said cap and a wedge-shaped member engaging the inner side of said washer.

3. In a carburetor, the combination with an air inlet passage, of a combined deflector and valve controlling said passage comprising spaced parallel disks the outer disk only

being adapted to close said passage, a hollow stem for said valve communicating with the space between said disks and having a normally open outer end, and means for 5 yieldably maintaining said outer disk in engagement with its seat.

4. In a carburetor, the combination with an air inlet passage, of a combined deflector and valve controlling said passage and 10 comprising spaced parallel disks, the outer of said disks only being adapted to close said passage, a hollow stem for said valve communicating with the space between said disks and having a normally open outer 15 end, means for positively closing said valve and means for closing the outer open end of said valve stem.

5. In a carburetor, the combination with an air inlet passage, of a valve controlling 20 said passage, comprising spaced inner and outer disks, the outer disk only of which is adapted to seat, and means permitting of the passage of air through said outer disk into the space between both of said disks.

25 6. In a carburetor, the combination with an air inlet passage, of a valve controlling said passage including spaced discs, one disc being adapted to seat, and means permitting of the passage of air through the 30 last mentioned disc into the space between both of said discs.

35 7. In a carburetor, the combination with a mixing chamber having a plurality of air inlet passages, of longitudinally adjustable spring influenced means for controlling the supply of air through one passage, a member for regulating the spring influenced means, and a member mounted on the last mentioned member for controlling the supply of air through the other passage.

40 8. In a carburetor, the combination with a mixing chamber having an air inlet provided with a valve seat, of a valve for controlling the passage of air through the inlet 45 including a pair of spaced discs, engageable with the seat, one disc having a passage therethrough and a stem provided with a longitudinal passage in communication with

the passage aforesaid, and a closure for the passage in the stem. 50

9. In a carburetor, the combination with a mixing chamber having an air passage leading thereto, of a valve controlling said passage, a stem for the valve, a guide for the stem carried by the chamber, a cap connected to the stem, a washer on the stem, a yieldable member between the washer and cap normally holding the valve closed, and means adjustable between the guide and washer for varying the movement of the 55 valve. 60

10. In a carburetor, the combination with a mixing chamber having an inclined wall forming a valve seat, and an air passage leading to the inclined wall, of a valve including spaced discs engageable with said inclined wall for controlling the flow of air through the passage to the chamber. 65

11. In a carburetor, the combination with a mixing chamber having an inclined wall 70 forming a valve seat and an air passage leading to the inclined wall, of a valve for controlling the flow of air through the passage to the chamber including inner and outer discs, the outer disc being adapted to 75 engage the seat when the inner disc is spaced therefrom, the outer disc having a passage therethrough and being spaced from the inner disc whereby air may pass through the outer disc and between the inner disc 80 and seat to said chamber.

12. In a carburetor, the combination with a mixing chamber having an air passage leading thereto, of a valve controlling said passage, a stem for said valve, a guide for the stem, a cap connected to the stem, a washer on the stem, a yieldable member between the washer and cap normally holding the valve closed, and a substantially wedge-shaped member adjustable between the 85 guide and washer for varying the movement of the valve. 90

In testimony whereof we affix our signatures.

EDWARD B. GIBFORD.

CHARLES WALKER GIBFORD.
